UNITED STATES PATENT OFFICE.

CHARLES D. McDONALD AND JOHN E. McCULLOUGH, OF CHICAGO, ILLINOIS, ASSIGNEES
TO McDONALD MACHINE CO., OF CHICAGO, ILLINOIS, A CORPORATION OF ILLINOIS.

DIE-PRESS MECHANISM.

Application filed February 6, 1922. Serial No. 534,337.

To all whom it may concern:

Be it known that we, CHARLES D. McDONALD and JOHN E. McCULLOUGH, citizens of the United States, and residents of Chicago, 5 Cook County, and State of Illinois, have invented certain new and useful Improvements in Die-Press Mechanism, of which the following is declared to be a full, clear, and exact description.

10 This invention relates to die press mechanism, and more particularly to the mechanism of multiple die or punch presses, which has to do with the feeding of the strips, sheets of metal or other work to the dies of the press. For the sake of economy of material and economy in time, die presses, of 15 the automatic type especially, are equipped with two or more sets of dies, whereby two or more punchings or stampings may be made during each stroke of the press. A comparatively long strip of material is usually employed and heretofore considerable time has been lost because it was found necessary to run the press idle at the time a 20 strip was being placed over a die after a preceding strip had been operated on.

25 It will be understood that, for the purpose of economy of material, especially when punching out circular or oval pieces, extremely narrow spaces are left between the 30 punched out pieces, and usually the punched pieces of one row are arranged midway between those of another row. As a consequence, and, further, because the dies must be spaced far enough apart to give body to 35 the female dies, it was found necessary when making the last punch in a strip, for one or more of the dies to remain idle during this stroke of the press, and when making the first punch in a succeeding strip, for one or 40 more of the dies to remain idle at this time also. As a result, there was a loss of time and useless wear and tear on the press.

In accordance with the present invention, 45 each stroke of the press is utilized to make two or more punches, one strip being fed to the dies before a preceding strip is completely punched out, and in such timed relation that the last punch in the outgoing strip is made simultaneously with the first punch 50 in the incoming strip. This we have accomplished by speeding up the strip feeding mechanism, and by providing novel means for enabling the incoming strip to be fed to 55 the dies without interference by the outgoing

strip. To enable all of the dies to operate when acting simultaneously on two strips, it is necessary for the incoming strip to slightly overlap the outgoing one and one of the principal difficulties encountered was the provision of guiding means which would function properly, irrespective of any irregularities or buckled or bent end portions of either strip.

60 The invention consists in a multiple die press mechanism, wherein the last and first punches on an outgoing strip and an incoming strip may be made simultaneously, whereby all of the dies may be utilized during each stroke of the press. It further consists in the provision of novel strip spacing means arranged to separate an incoming strip from an outgoing one during the interval that an incoming strip is carried to overlap an outgoing one. It further consists in 65 the several novel features hereinafter fully set forth and claimed.

70 The invention is clearly illustrated in the accompanying drawings, in which:

75 Fig. 1 is a front elevation of a die press mechanism equipped with one embodiment of the present invention; Fig. 2 is a view partly in front elevation and partly in vertical, longitudinal section through the strip feeding mechanism; Fig. 3 is a plan of two strips and two female dies of a press mechanism, showing the strips in the position occupied when about to be acted on by the duplex dies; Fig. 4 is a plan of fragments of 80 said strips, and the female dies showing the strips in position just before they are fed to the position shown in Fig. 3; Fig. 5 is a detail cross-section taken on line 5—5 of Fig. 6; Fig. 6 is a plan of a fragment of the feed table, dies and discharge chute, and two 85 strips, with the invention applied thereto; Fig. 7 is a front elevation of the parts seen in Fig. 6; Fig. 8 is a perspective view of a strip feed finger equipped with a guard forming part of the invention; and Fig. 9 is 90 a perspective view of another guard member for spacing the strips apart at the place where one overlaps the other.

95 Referring to said drawings, which illustrate a simple embodiment of the present invention, the reference character 10 designates, generally, an automatic die press mechanism, which is here shown in skeleton or fragmentary form. The construction of 100 the press mechanism chosen to illustrate this 105 110

invention is more fully shown and described in a prior Patent No. 1,421,271, issued to C. D. McDonald and C. E. Ennes, dated December 15, 1914, to which reference is herein made. In the press shown herein and also in said patent there is a reciprocating press head, indicated by 11 in the drawings, accompanying the present specification, which head carries two male dies 15, 15^a, that co-operate with two female dies 16, 16^a, mounted on the bed or base plate 12 of the press frame 13. At one side of the dies is a feed table 14 upon which is placed a bundle or stack of strips or other work, which is to be punched or blanked out by the press, and co-operating with said dies is strip inserting mechanism, *a*, *b*, which operates to take one strip at a time (from said bundle of strips) and place it in a feedway, in position to be fed in a step by step manner to the dies by the strip feeding mechanism.

As in the prior patent referred to, the strip feeding mechanism may comprise a reciprocable feed bar 18, guided to move in a suitable guideway 18^a of the feed table, and operated from the driving mechanism *c* of the press by a connecting rod 26, a bell crank lever 25 connected to its lower end and fulcrumed on the press frame 13, and a link connection 23, which is secured to one arm of the bell crank lever 25 and to an ear or lug 41 of the feed bar mechanism. The ear or lug 41 is secured upon a threaded stem 17 which is secured to and projects from the feed bar 18.

The feed bar 18 contains a plurality of spaced fingers 27, 28, 28^a, which are pivotally mounted on blocks 43 secured to the feed bar 18 and arranged along its length in spaced relation to each other. Their effective ends or tips project into a slot *d* in the feed table and successively engage with the strips or other work to feed it in a step by step manner to the dies. The fingers are spring pressed into the slot *d* by springs confined between the lower end portions of the fingers and the blocks 43. As in the press of the prior patent referred to, the finger 27 (which first engages the strip and which may be termed the initial feed finger) has a greater range of movement than the other fingers 28, 28^a, in order to bring the strip over the die 16, which makes the first impression on a strip. The means for effecting this additional length of stroke of the finger 27 may comprise a lever 35 connected to the finger actuating block 33 of the finger 27 by a link 34, and, an operating link 40 secured to and extending between the ear or lug 41 and lever 35. The lever 35 is fulcrumed on a bracket 36 secured to the press frame, and the link 40 is connected to the lever 35 between its fulcrum and point of connection with the link 34.

It is perfectly apparent from the above

that in the operation of the press mechanism described, strips or sheets of material are fed to the dies in a step by step manner, and are acted on by the dies each time the strip is fed forward one step. On each stroke of the feed bar, the strip is fed forward a distance slightly greater than the size of the piece punched out of it, so as to leave a thin web between resulting holes. The dies are placed along a diagonal line and the location of the dies is calculated so as to bring the punched holes of one row intermediate those of the other row. In the operation of the press described, the first punch made is the one indicated by the reference character *e* and this punch is made by the dies 15, 16. When the strip is fed forward one step, it brings the strip over both dies 16, 16^a, at the position shown in Fig. 3. In this position both dies 15, 15^a, 16, 16^a, act on the strip and punch the metal out at the places lettered *f*, *f'*. The places lettered *g*, *g'*, are the last double punches made in the strip, and the one lettered *h* is the last single punch made in it. The press mechanism briefly described above is more fully illustrated and described in the prior patent above referred to. The present invention is illustrated in connection with the press disclosed in said patent, because it is one of a type of presses which is well adapted for use in connection with the present invention. It is not our intention to limit ourselves to the use of the present invention to the press described, as it is perfectly obvious that it is capable of use in connection with other forms of automatic die press mechanism using a step by step feed mechanism for feeding the strips or other work to the dies.

We shall now proceed to describe in detail the embodiment of the present invention which is illustrated in connection with the press above set forth.

The finger 28^a of the feed mechanism is the one which is the last one of the series of fingers that engages the strip or other work in feeding it to the dies. When this finger 28^a does its work all of the punches have been made in an outgoing strip, except the last one at *h*, and this position of the outgoing strip is seen in Fig. 3. The strip inserting mechanism *a*, *b*, of the press at this time is put into operation and a strip A is taken from the bundle or stack and inserted into the feed slot *d*, in position to be engaged by the initial feed finger 27 (which is then in the position seen in Fig. 1) a fragment of the strip being illustrated in Fig. 4, in approximately the position it occupies after the last double punchings have been made in the outgoing strip B, and before both incoming and outgoing strips are fed forward.

Referring to said Fig. 4, it is obvious that

if the incoming strip is moved over the female die 16 while any part of the outgoing strip is still over said die, the work is liable to become jammed because the two strips are normally guided to lie in the same plane and the forward edge of the incoming strip would strike the rear edge of the outgoing strip, particularly if either were slightly buckled out of its plane or either corner 10 were bent ever so slightly. The result would cause further buckling or bending of the strips, jamming of the work in the press proper and feedway, with the loss of a strip of material, and the necessity of stopping 15 the press until a skilled attendant could extricate the damaged strips and start the press. Moreover, in such cases, there would always be the danger of serious injury to the press itself. We have made it possible 20 to feed the incoming strip over the end portion of the outgoing strip without any possibility of the work jamming at this place, by providing guide or guard members on the last feed finger 28^a and on some stationary part of the press, which guide or guard 25 members space one strip from the other at the time the forward end of the incoming strip passes over the rear end of the outgoing strip.

Referring now to Figs. 6 and 8, the last finger 28^a, while constructed in the main part like the other or intermediate fingers 28, and while connected to the feed bar in the same manner, is provided with a guard 28^b, which overhangs its effective end or tip 28^c and projects laterally thereof to one side in the form of a thin web, which is somewhat wider at the place where it joins with the body of the finger than at its extreme 30 end, which leaves a diagonally extending edge portion 28^d. The guard 28^b overlies the rear edge of the outgoing strip (when said finger 28^a feeds it forward) and covers any upturned rear edge portions of the outgoing 35 sheet. Moreover, an incoming strip in passing over said guard will freely pass the guard because there is no possibility of any ragged edge portion of the incoming strip catching on the diagonal edge 28^d. Moreover, the guard 28^b raises the forward edge 40 of the incoming strip a distance equal to or slightly more than the thickness of the guard 28^b, thus insuring its passage (at least at that place) over the rear edge of 45 the outgoing strip.

At the opposite side of the feedway for the strip is a guard 29, (see Figs. 5, 7, and 9,) which is secured to the discharge end of the feed table 14. Said guard 29 has a web-like portion 29^a, one end of which is located slightly below the normal plane of travel of the strip and the other end of which is located above the normal plane of travel of the strip. It is set in the normal 55 path of travel of the incoming strip so that

the latter on passing said web portion 29^a of the guard is deflected upwardly, thereby insuring its free movement over the rear end of the outgoing strip. The web 29^a is preferably made of resilient material, 70 whereby it may yield downwardly under the influence of great force, such for instance as is occasioned by the male die 15. Referring now to Fig. 9, the lower end of the web portion 29^b is secured to the underside 75 of a laterally movable guard member supporting block 29^c, which is slidably mounted on a supporting bracket 29^d, and spring pressed toward the strip or other work by a coiled spring 29^e (see Fig. 5) interposed 80 between the block 29^c and bracket 29^d. A pin and socket connection 29^f between the block and bracket 29^d limits the movement of the block 29^c. The bracket 29^d is adjustably supported on the feed table by 85 bolts 29^f that extend through a slot in the tail 29^g of the bracket and are threaded in the feed table, and if desired, said bracket 29^d may be made of two pieces 29^h, 29ⁱ, to provide for a limited amount of adjustment 90 of the part 29^h of the bracket in a line running parallel with the work. These two parts 29^h, 29ⁱ, of the bracket are secured together by a bolt or otherwise, as desired. A guide groove 29^j is formed in the front 95 or strip engaging face of the block 29^c, in line with the feed slot, whereby the side edge of the strip will be guided, after it leaves the feed slot, by said block 29^c, to the guard member 29^a. The guard member 100 29^a extends part way past the female die 16 and operates to raise the adjacent edge portion of the incoming strip above the rear edge of the outgoing strip. The guard terminates at a point where the rear 105 edge of the outgoing strip may drop from the guard before the forward elevated end reaches the outgoing strip. The edges at the ends of an outgoing strip and an incoming strip are thereby spaced away from each 110 other at the place where one passes the other, which leaves the incoming strip free to move forward over the die 16.

A strip holding finger 30 is pivotally supported on the feed table, between ears 30^a, 115 and is spring pressed in a downward direction by a spring 30^b, confined between the top of the finger 30 and a nut 30^c on a post 30^d. Said strip holding finger 30 extends forward between the dies and terminates at 120 a point to one side of the die 16^a, where it bears upon the strip and holds it down against the die.

In the operation of the press mechanism, the feed bar 18 is reciprocated once for each stroke of the press head, and in timed relation thereto. The strip inserting mechanism *a, b*, is timed to insert a strip into the feed slot in time to be acted on by the initial feed finger 27 simultaneously with 130

the action of the last finger 28^a on an outgoing strip. This position of the strips is seen in Fig. 4, and the forward movement of the feed bar brings the two strips into the position seen in Fig. 3, where the last punch of the outgoing strip is done, and simultaneously therewith the first punch on the incoming strip is done. In passing to this position, the rear end of the outgoing strip is held under the guard of the finger 28^a, thereby permitting the front end of the incoming strip to freely pass over said rear end of the strip, and the other side edge portion of the incoming strip is raised by the guard member 29^a as it passes over the rear edge portion of the outgoing strip. The possibility of collision between the two strips is thereby eliminated and no loss of time is occasioned in the work of the press, each stroke of the dies being utilized at the ends of the strips as well as at all other places between the ends.

While the invention has been shown and described in connection with duplex die press mechanism, it is to be observed that two or more sets of dies may be used for punching along two or more rows. It is also to be understood that the strip feed mechanism illustrated and described is immaterial to the invention, as any suitable strip feed mechanism may be substituted for the present one.

More or less variation of the exact details of construction is possible without departing from the spirit of this invention, we desire, therefore, not to limit ourselves to the exact form of the construction shown and described, but intend, in the following claims, to point out all of the invention disclosed herein.

We claim as new and desire to secure by Letters Patent:

1. In multiple die press mechanism, the combination with multiple die mechanism, of strip feeding mechanism having means for simultaneously feeding two strips to the dies, one strip following the other, but at greater speed, whereby the latter strip overlaps the preceding strip between the dies, thereby permitting the dies to simultaneously act on the end portions of both strips.

2. In multiple die press mechanism, the combination with multiple die mechanism, of strip feeding mechanism, arranged to feed strips of material to the dies, in a step by step manner, with the front ends of the succeeding strips overlapping the rear ends of the preceding ones at the dies, whereby the dies may simultaneously act on the end portions of both strips, and a guide for spacing apart the said end portions of the strips at the place where they overlap.

3. In multiple die press mechanism, the combination with multiple die mechanism, of strip feeding mechanism, arranged to

feed a strip to the dies of said die mechanism, in a step by step manner, said strip feeding mechanism having an initial feed finger and a last feed finger, capable of simultaneously feeding forward two strips. 70 the stroke of the initial feed finger being greater than that of the last feed finger, whereby the front end of one strip is carried over the rear end of the other strip, and a guard for spacing apart the said end portions of the strips, at the place where the one passes the other. 75

4. In multiple die press mechanism, the combination with a guideway for the strips to be operated on and multiple die mechanism, embracing spaced dies, of strip feeding mechanism arranged to feed a strip along said guideway to said dies in a step by step manner, said strip feeding mechanism having an initial feed finger and a 80 last feed finger capable of simultaneously feeding two strips to said dies, the stroke of the initial feed finger being longer than that of the last feed finger, whereby the rear end of one strip is carried over one of said dies and simultaneously the forward end of the other strip is carried over the other die and over said rear end of the first mentioned strip, and a guard for spacing apart said end portions of the strips at the place 95 where the one passes over the other.

5. In multiple die press mechanism, the combination with a guideway for the strips to be operated on and multiple die mechanism, embracing two or more spaced dies, 100 of strip feeding mechanism arranged to feed a strip along said guideway to said dies in a step by step manner, said strip feeding mechanism having an initial feed finger and a last feed finger capable of simultaneously feeding two strips to said dies, the stroke of the initial feed finger being longer than that of the last feed finger, whereby the rear end of one strip is carried over one of said dies and simultaneously the forward end of the other strip is carried over the other die and over said rear end of the first mentioned strip, and a guard on said last feed finger arranged to overlie the adjacent end portion of a strip when said finger is engaged therewith, said guard acting to space an oncoming strip from the strip engaged by said last feed finger. 110 115

6. In multiple die press mechanism, the combination with a guideway for the strips to be operated on and multiple die mechanism, embracing two or more spaced dies, of strip feeding mechanism arranged to feed a strip along said guideway to said dies in a step by step manner, said strip feeding mechanism having an initial feed finger and a last feed finger capable of simultaneously feeding two strips to said dies, the stroke of the initial feed finger being longer than that of the last feed finger, whereby the 120 125 130

rear end of one strip is carried over one of said dies and simultaneously the forward end of the other strip is carried over the other die and over said rear end of the first 5 mentioned strip, and a guard formed on said last feed finger, arranged to overlie the adjacent end portion of a strip when said finger engages therewith, said guard having a diagonally extending rear edge substantially as and for the purpose specified. 10

7. In multiple die press mechanism, the combination with a guideway for the strips to be operated on and multiple die mechanism, embracing two or more spaced dies, of
15 strip feeding mechanism arranged to feed a strip along said guideway to said dies in a step by step manner, said strip feeding mechanism having an initial feed finger and a last feed finger capable of simultaneously
20 feeding two strips to said dies, the stroke of the initial feed finger being longer than that of the last feed finger, whereby the rear end of one strip is carried over one of said dies and simultaneously the forward end
25 of the other strip is carried over the other die and over said rear end of the first mentioned strip, and a guard having an inclined part lying in the path of movement of a strip at the place where one strip passes over
30 the other.

8. In multiple die press mechanism, the combination with a guideway for the strips to be operated on and multiple die mechanism, embracing two or more spaced dies, of strip feeding mechanism arranged to feed a strip along said guideway to said dies in a step by step manner, said strip feeding mechanism having an initial feed finger and a last feed finger capable of simultaneously

feeding two strips to said dies, the stroke of the initial feed finger being longer than that of the last feed finger, whereby the rear end of one strip is carried over one of said dies and simultaneously the forward end of the other strip is carried over the other die and over said rear end of the first mentioned strip, and a spring pressed laterally movable block and an inclined resilient guard member secured to said block and lying in the path of movement of a strip at the place where one strip passes over the other. 40 45 50

9. In multiple die press mechanism, a last feed finger formed with a laterally projecting web like guard adapted to overlie a corner portion of a strip engaged by said finger. 55

10. In multiple die press mechanism having a straight guideway, a guard for spacing apart overlapped strips adjacent said guideway, comprising an inclined flexible guard member at the end of said guideway over which the work passes and by which it is deflected slightly out of its normal course when emerging from said guideway. 60

11. In multiple die press mechanism, a ⁶⁵ guard for spacing apart overlapped strips, comprising a spring pressed laterally movable block, and an inclined, resilient guard member secured thereto.

12. In multiple die press mechanism, a 70
guard for spacing apart overlapped strips,
comprising a spring pressed laterally movable
block, formed with a guide groove in its
face, and an inclined, resilient guard mem-
ber secured thereto below said guide groove. 75
